HARVEY SLATER, OF CHICAGO, ILLINOIS, ASSIGNOR TO CHARLES F. ELMES ENGINEERING WORKS, OF CHICAGO, ILLINOIS, A CORPORATION OF ILLINOIS.

VALVE CONTROL.

1,184,143.

Specification of Letters Patent. Patented May 23, 1916.

Application filed September 3, 1914. Serial No. 859,970.

To all whom it may concern:

Be it known that I, HARVEY SLATER, a citizen of the United States, and resident of Chicago, in the county of Cook and State 5 of Illinois, have invented certain new and useful Improvements in Valve Control, of which the following is a specification.

My invention relates to devices for controlling high pressures and particularly relates to 10 valvular devices employed in controlling hydraulic machines, such as rams and presses which are subjected to extremely high pressures and the invention constitutes an improvement in the device illustrated in 15 my Patent No. 1,143,236 granted June 15, 1915.

Heretofore great difficulty has been experienced with devices of this character subjected to high pressure largely on account 20 of the difficulty in actuating the valves manually and the tendency of such valves to leak, and if made large enough to operate easily under working conditions, the difficulty of controlling the same readily and 25 rapidly, especially if the working parts are constructed to fit tightly is greatly increased.

One of the primary objects of my invention is to provide a manually actuated control 30 for operating different high pressure inlets and which can be controlled by the movement of a single operating handle or lever in such a manner as to open successively the different inlet valves or the exhaust or 35 to close all the passages through the device gradually in each case, with fine regulation and control and without the exercise of more than ordinary precaution on the part of the operator.

40 A further object of my invention is to provide a construction in which a limited amount of independent movement is provided between the different valves of the device, which permits the mechanism to be 45 controlled easily, and at the same time, permits a certain amount of automatic adjustment of the parts.

50 A further object of the invention is to provide means whereby devices may be opened to extremely high pressures without the necessity of the valves overcoming this high pressure on their initial opening movement.

55 The various other objects of the invention will be more fully set forth in the following description of one form of valve embodying

my invention, together with certain modifications thereof, which consists in the new and novel features of construction and combinations of parts hereinafter set forth and claimed.

In the drawings:—the figure is a longitudinal sectional view through a preferred form of my invention particularly adapted for extreme high pressure work.

There is shown a casing 1, into one end 60 of which is inserted a screw plug 2, which casing has a relatively low pressure inlet 3, a machine supply port 4 and an exhaust 5, disposed in order longitudinally of the side of the casing. The casing may also have a 65 port 6 for connection with a pressure gage or other suitable indicator. The bore of the casing between the inlet 3 and the port 4 has an apertured partition 7, forming a guide and seat for the main inlet controlling valve 75 8, which valve has extending therethrough one of the alined stems of a pilot valve 9, the other outwardly extending stem 10 of which is guided in a bore 11 extending through the plug 2 and is engaged by the compression 80 spring 12, which acts upon the pilot valve and through the pilot valve on main valve 8, tending to maintain the same in closed position.

The portion of the bore of the casing 1 between the port 4 and exhaust 5 is constricted to form a shoulder 13, and disposed in this portion of the bore is a guiding sleeve 14 bearing upon a packing 15, positioned between the sleeve 14 and the shoulder 13. 85 90 Slidably mounted in the sleeve 14 and adapted to be brought into engagement with the upper stem of the pilot valve 9 and with the top of the main valve 8 is a sliding piston 16, having a passageway 17 extending 95 therethrough and adapted to place the port 4 in fluid communication with the exhaust 5. A bonnet 18 is threaded into the end of the casing opposite the plug 2, the lower end of which bonnet provides a seat 19 forming 100 a stop for the upward movement of the piston 16. Extending through the bonnet 18 and in threaded engagement therewith is a screw rod 20, the lower end of which is formed into or is in bearing engagement 105 with an exhaust controlling valve 21, adapted to close fluid communication through the passageway 17. The rod 20 may be actuated by any suitable means, and for this purpose a manually actuated handle 22 is 110

110

provided. The length of the piston 16 is so proportioned that the main valve and pilot valve may move into closed position before the piston engages with the seat 19.

5 The bore 11 through the plug 2 constitutes an inlet conduit for the relatively high pressure fluid controlled by the device and is countersunk from the outer end to form a cylindrical chamber 23 in which is fitted 10 a barrel 24 one end of which constitutes the valve seat for the relatively high pressure controlling valve 25, which has a closing movement onto its seat in the direction toward the pilot valve 9.

15 The valve 25 has a stem 26 guided in the bore 11 and terminating a short distance from the stem 10 of the pilot valve 9 when the valves are in their normal closing position. The barrel is held in position by a 20 ring 27 fitted into a peripheral groove therein, which ring is held in place by a coupling 28 threaded into the outer end of the plug 2. The coupling has a bore 29 constituting a continuation of the bore 11 25 and the inner end of the bore 29 is countersunk to provide a spring housing and guide for the outer portions of the valve 25. A relatively strong spring 30 is contained within the housing and bears on the valve 30 25 to maintain the same firmly on its seat.

The valve 25 is provided with a passageway 31 which places the bore 29 in communication with the portion of the bore 11 in advance of the valve seat and a plurality of by-passes 32 places the portion of the bore 11 in rear of this valve seat in communication with the port of the bore 11 in advance of the main valve 8. A one-way check valve 33 is placed in the inlet 3 to 35 prevent the high pressure from passing in a reverse direction through said inlet.

With the parts in the position indicated, the valves 8 and 9 are in position closing communication between the inlet 3 and machine supply port 4 and the valve 25 is in 45 position closing the high pressure inlet. The piston 16 is in engagement with its seat 19, and the valve 21 is in position closing communication between the port 4 and exhaust 5. Rotating the handle 22 in a direction to move the screw rod 20 downward moves the piston 16 off its seat, and into engagement with the pilot valve 9, unseating the same and permitting the equalization 50 of pressure on opposite sides of the main valve 8 and the continued movement of the piston 16 will act on the valve 8 to unseat the same, permitting the full head of pressure from the inlet 3 to pass the main inlet 55 controlling valve. At this time, the valve 21 is in position, closing communication between the port 4 and exhaust 5.

A still further rotation of the rod 20 will cause the stem 10 to press on the stem 26 60 thereby to unseat the valve 25 controlling

the high pressure inlet. The pressure of the fluid entering through the bore 29, bypass 32 and bore 11, being greater than the pressure through the inlet 3, will act to close the check valve and the higher pressure is open to the machine port. 70

The actuating of the handle to move the screw rod 20 in the opposite direction will permit the pressure from the supply port 4 to act on the plunger to move the same 75 toward its seat, thus permitting first, the closing of the valve 25 by its spring 30 and then, the closing of the valves 8 and 9 in succession by their controlling spring 12. The valve 8 is completely seated, preferably 80 just before the piston 16 reaches its seat, and at this time, the valve 21 is in position closing the passageway 17. A further movement of the rod 20 permits the piston to move into engagement with its seat, during 85 which time the machine supply port is shut off from both the inlets and exhaust. A further movement outward of the screw rod will either positively lift the valve 21 from 90 its engagement with the piston, or permit the valve to be raised by the pressure from the port 4 so that there will be free fluid communication with the machine supply port 4 to the exhaust 5 through the passageway 17. 95

By means of this construction, both the inlet valves and the outlet valve can be closed and the pressure in the machine held stationary by movement of the handle which will permit the inlet valves to close without 100 allowing the plunger to rise against its seat on the casing, whereby the outlet valve is also held in engagement with its seat in the piston. Since an independent stop is thus provided for the piston, the inlet valves 105 each have an independent movement relative thereto, and to each other thus permitting the same to close automatically when the pressure against the piston is released and allowing complete disengagement between 110 these parts for any desired interval prior to the instant when the piston engages with the stop or shoulder in the casing. Consequently, it is possible to pack the piston in a simple and effective manner, since the 115 packing is firmly held between the shoulder stationary with respect to the casing, and thus allowing the packing to be arranged so that the pressure from the machine will tend to make a tight joint. The pressure receiving areas, both of the different inlet valves and the outlet valve, are comparatively small, so that the pressure to be overcome in the movement of these valves is correspondingly decreased. 120

Should it be desired to use only the pressure from the relatively low pressure inlet 3 it is necessary merely to rotate the handle over an angular distance sufficient to unseat the main inlet controlling valve, the stem of 130

this main valve being spaced from the high pressure controlling the valve 25 so that a material movement is necessary before the extreme high pressure inlet is opened.

- 5 By means of a device of this character it is possible to open the machine to extremely high pressure with but little effort as the successive movements of the different inlet valves are against a head equal to the differences in pressure on opposite sides of the succeeding valves and each valve is completely open before the next succeeding valve is actuated. All of the valves have a straight line movement in the direction of feed of the rod so that all of the manual force exerted on the handle is directed straight against the different inlet valves. The different valve carrying elements may be removed as units in case it should become necessary to repair or replace the valves or grind the valves and their seats.

While but two inlets have been shown it is obvious that with the necessary mechanical changes in construction, any number of inlets may be arranged to be successively opened to the devices and it is obvious that various other changes within the skill of the mechanic may be made without departing from the spirit of my invention, provided the means set forth in the following claims be employed.

Having thus described my invention, I claim:—

1. In a valve mechanism, the combination with a casing having a machine supply port, a relatively low pressure inlet and an exhaust, a normally closed main valve for said inlet, a floating piston between said port and exhaust, an exhaust controlling valve, a relatively high pressure inlet and a normally closed valve for said high pressure inlet, of means adapted to be moved in one direction to move said piston from an inoperative position into engagement with said main valve to open the same, and to move said main valve to open said high pressure valve, said means being adapted to be moved in a reverse direction into position to form a stop for said floating piston in its movement out of valve opening engagement with said inlet valves and adapted to be moved into another position to permit unseating of said exhaust controlling valve.

2. In a valve mechanism, the combination with a casing having a machine supply port, a plurality of pressure inlets to said port, a normally closed main valve controlling all of said inlets, a normally closed pilot valve for equalizing pressures between said port and said inlets, a supplemental valve for controlling one of said inlets, of an actuating means movable in one direction to open successively said pilot valve, said main valve and to move said pilot valve into position to open said supplemental valve in order.

3. In a valve mechanism, the combination with a casing having a bore extending therethrough, a machine supply port, a low pressure inlet and an exhaust communicating with said bore, a screw plug in one end of said bore, a main inlet controlling valve supported by said plug, a bonnet having a screw rod closing the other end, guiding means within said bore between said bonnet and said port, a high pressure conduit through said plug, a valve controlling said high pressure conduit, a floating piston guided in said means and adapted to actuate said main valve and said high pressure valve in succession and an exhaust controlling valve operatively engaged by said screw rod to actuate said piston.

4. In a valve mechanism, the combination with a casing having a bore extending therethrough, provided with a machine supply port, a plurality of pressure inlets and an exhaust leading to said bore, of a screw plug inserted in one end of said bore, inlet controlling valves supported by said plug, a bonnet having a screw rod closing the other end, said bonnet having a piston seat, a piston floating between said port and seat and adapted to actuate said inlet controlling valves, an exhaust controlling valve adapted to be moved by said screw rod to unseat said piston and actuate said inlet controlling valve.

5. In a valve mechanism, the combination with a casing having a bore extending therethrough, a machine supply port, a low pressure inlet and an exhaust leading to said bore, of a spring pressed inlet controlling valve in said bore between said low pressure inlet and port, a high pressure inlet leading to said bore, a valve controlling said high pressure inlet, a floating piston in said bore having a passageway extending therethrough placing said port in fluid communication with said exhaust, and a manually controlled valve for said passageway to move said piston into position to open said low pressure inlet controlling valves and to move said low pressure controlling valve into position to open said high pressure controlling valve.

6. In a valve mechanism, the combination of a casing having a machine supply port, a plurality of pressure inlets and an exhaust, a spring pressed inlet controlling valve, a main inlet controlling valve, one of said inlets opening to the bore between said valves, a floating piston having means for placing said port in communication with said exhaust, a stop for said piston, an exhaust controlling valve, and a screw rod adapted to actuate said exhaust controlling valve and to move said piston out of engagement with said stop and into operative engagement with said inlet controlling valves to open the same successively.

7. In a valve mechanism, the combination with a hollow casing having a low pressure inlet, a machine supply port, and an exhaust disposed in order longitudinally of the casing, of a normally closed valve between said low pressure inlet and said port, a sliding piston between said port and exhaust having means for placing said port and exhaust in fluid communication, a valve 10 adapted to engage said piston controlling said exhaust, manually actuated means adapted to act on said exhaust controlling valve to close communication between said port and exhaust, and adapted to move said piston into engagement with said low pressure inlet controlling valve to open the same, a check valve in said low pressure inlet preventing communication therethrough from said high pressure inlet, a normally closed 15 valve controlling said high pressure inlet controlled by the movement of said manually actuated means for opening said high pressure controlling valve.
8. In a valve mechanism, a casing having a bore extending therethrough, a machine supply port and a pressure inlet to said bore, a plug disposed in one end of said bore, said bore being restricted between said ports to form a valve seat, a main valve guided in 20 said restricted bore and normally resting against said seat, an auxiliary valve positioned in said main valve and having a stem extending therefrom past said inlet port and guided in said plug, a spring completely 25 housed within and removable with said plug and acting on said stem tending to maintain said auxiliary and main valves in position closing communication between the inlet and machine supply ports, a second inlet 30 through said plug, a valve controlling said second inlet, a spring housed in said plug for tending to maintain said second valve in closed position and manually controlled means bodily movable in the unseating di-

rections of said valves to move into successive positions thereby to open communication between the inlets and the port.

9. In a valve mechanism, a casing having a bore extending therethrough, a removable plug at one end of said bore, a bonnet having a screw rod closing the other end, said casing having a machine supply port and a plurality of pressure inlets, the bore being reduced between said port and inlets to form a valve seat, a main valve bearing on said seat, an auxiliary valve within said main valve resiliently supported from said plug and removable therewith, a second inlet controlling valve contained in said plug and removable therewith, a piston adapted to be moved by the actuation of said screw rod into position to open said auxiliary and main valves in succession, and said auxiliary valve adapted in its opening movement to open said second valve, an exhaust from 55 said bore and a valve for controlling said exhaust operatively connected to said screw rod.

10. In a device of the class described, the combination with a main valve, a second valve spaced from the main valve in the direction of the opening movement of said main valve, an inlet between said valves, a check valve in said inlet, closed when said second valve is open, a conduit controlled 70 by said second valve and manually controlled means movable in the direction of the opening movements of said valves to successively open said main valve and said second valve in order.

Signed at Chicago, in the county of Cook and State of Illinois this 26th day of August A. D., 1914.
